UNITED STATES PATENT OFFICE

146,761

DESIGN FOR A BRACELET OR THE LIKE

Michael Chernow, New York, N. Y.

Application November 9, 1945, Serial No. 123,610

Term of patent 7 years

(Cl. D45—4)

To all whom it may concern:

Be it known that I, Michael Chernow, a citizen of the United States and residing at New York, in the county of New York and State of New York, have invented a new, original, and ornamental Design for a Bracelet or the like, of which the following is a specification, reference being had to the accompanying drawing, forming part thereof, and in which

Fig. 1 is a plan view of the bracelet or the like, showing my new design, and

Fig. 2 is a side elevation thereof.

I claim:

The ornamental design for a bracelet or the like, substantially as shown.

MICHAEL CHERNOW.
